United States Patent Office

Des. 224,712
Patented Sept. 5, 1972

224,712

DICTATING MACHINE

Rebertus van de Poel, Eindhoven, Netherlands, assignor
to United States Philips Corporation

Filed Feb. 4, 1971, Ser. No. 112,843

Claims priority, application Switzerland Aug. 12, 1970

Term of patent 14 years

Int. Cl. D14—01

U.S. Cl. D26—14

FIG. 1 is a perspective view of the dictating machine showing my new design;

FIG. 2 is a right side elevational view;

FIG. 3 is a left side elevational view;

FIG. 4 is a front elevational view;

FIG. 5 is a rear elevational view;

FIG. 6 is a top plan view;

FIG. 7 is a bottom plan view.

I claim:

The ornamental design for a dictating machine, as shown.
